UNITED STATES PATENT OFFICE.

WILLIAM M. KELLY, OF JERSEY CITY, NEW JERSEY, ASSIGNOR TO AMERICAN TYPE FOUNDERS COMPANY, OF JERSEY CITY, NEW JERSEY, A CORPORATION OF NEW JERSEY.

PRINTING PRESS.

Application filed February 20, 1914. Serial No. 820,042.

To all whom it may concern:

Be it known that I, WILLIAM M. KELLY, a citizen of the United States, and resident of Jersey City, Hudson County, State of New Jersey, have invented certain new and useful Improvements in Printing Presses, of which the following is a specification.

This invention relates to printing presses and more especially to the two revolution

10 type of press in which there is a reciprocating bed and a continuously rotating cylinder which makes two revolutions for each reciprocation of the bed, the cylinder being lowered for the printing stroke of the bed and 15 raised during the return stroke.

One of the objects of the invention is to provide an improved automatic paper feeding mechanism which may be readily removed to permit hand feeding without dis- 20 turbing the driving means.

25 A further object is to provide an improved mounting for the feed board whereby it may be swung upwardly to permit access to the inking mechanism.

25 A further object is to provide improved side registering mechanism which will be reversible to permit the sheets to be registered on either side of the feed board.

30 A further object is to provide improved tripping mechanism which will be adapted to automatically prevent the lowering of the cylinder when a sheet of paper has not been fed thereto and which will also permit the cylinder to be raised at any time when it is 35 in the lowered or printing position.

Other objects and features of novelty will appear from the following description, taken in connection with the accompanying drawings, in which

40 Figure 1 is an elevation of the right hand side of a printing press embodying my improvements;

Figure 2 is an elevation of the left hand side thereof;

45 Figure 3 is a plan view of the printing press;

Figure 4 is an enlarged vertical section on the line 4—4 of Figure 3;

Figure 5 is a section on the line 5—5 of 50 Figure 3 and showing the right end of the impression cylinder in elevation;

Figure 6 is a section on the line 6—6 of Figure 5 and also showing some of the feed- 55 ing mechanism;

Figure 7 is a perspective view of one of the toggle mechanisms for lowering the impression cylinder;

Figure 8 is a detail of one of the impression cylinder journal boxes and a portion of the raising and lowering mechanism 60 therefor.

Figure 9 is an enlarged elevation of lever 142.

Referring to the drawings, 40 represents the frame or base casting of the press and 65 this frame has secured thereon the vertical brackets 98 and 99 which have vertical slots in their upper ends for the bearing boxes 100 and 101. The bearing boxes 100 and 101 have journaled therein the shaft 102 of the 70 impression cylinder 103. It is necessary to lower the impression cylinder for the printing operation and then raise the cylinder slightly to permit the reversal of the bed and return stroke. In order to effect this 75 raising and lowering of the impression cylinder the boxes 100 and 101 are arranged to slide in the brackets 98 and 99. Referring to Figures 6 and 8, it will be seen that on the top of the box 100 is a cross-bar 104, and 80 this bar has in engagement with its end portions the vertical bolts 105 and 106 which extend downwardly through the bracket 98 and project from the lower end thereof, and have secured to their lower ends a yoke 107. 85 The journal box 101 has associated therewith a mechanism similar to that just described, a part of this mechanism being shown in Figure 2. As shown in Figure 2, the vertical bolts 108 and 109 are connected with a 90 yoke 110, this yoke having a central recess 111 which receives the toggle member 112. The yoke 107 has a similar recess to receive a similar toggle member 112 as shown in Figures 6 and 7. The toggle members 112 95 cooperate with similarly formed but reversely arranged toggle members 113, which engage recessed blocks 114 in the brackets 98 and 99. As shown in Figures 2, 6 and 7, the toggle members are in their closed position 100 and have between them cylindrical pins 115 having their ends engaged by the forked ends 116 of horizontally extending links. From Figure 7, it will be seen that the toggle members when in closed position are 105 spaced apart along one side as shown at 117 so that the toggles will open to a position where the adjacent faces engage and close

the space indicated at 117. Referring to Figure 6 it will be observed that a screw 118 is secured in the bracket 98 by means of a lock nut 119. This screw is provided with a collar 120 adapted to be engaged by a suitable instrument to adjust the screw 118 in the bracket 98. A collar 121 is threaded onto the upper portion of the screw 118 and between this collar and the box 100 is a spring 122, the tension of the spring being adjustable by means of the collar 121.

Referring to Figure 1, it will be seen that one of the toggle operating links is shown at 123, the outer end of this link being pivoted to an arm 124 on the shaft 125. In Figure 2, the toggle operating link 126 is shown, this link being pivoted to an arm 127 on shaft 125. The shaft 125 also carries an arm 128, this arm having at its lower end a laterally projecting pin 129 adapted to be engaged by the hook 130 on the link 131, the latter being pivoted at 132 to a lever 133. The lever 133 is pivoted to the frame 40 at 134 and carries at its lower end a cam roller 135. The cam roller 135 engages a cam groove 136 on the inner side of a wheel 137 carried by the shaft 69. The cam groove 136 is so formed that the lever 133 is oscillated as the wheel 137 is rotated. The oscillation of the lever 133 gives an oscillatory movement to the shaft 125 and thus moves the links 123 and 126 to and fro to open and close the toggles. When the toggles are closed the yokes 107 and 110 are moved downwardly and the movement of these yokes is transmitted to the journal boxes 100 and 101 by means of the bolts 105, 106, 108 and 109. The closing of the toggles therefore lowers the impression cylinder and when the toggles are opened, the springs 122 lift the cylinder, the extent of the lifting movement being limited by the adjacent faces of the toggles coming together to close the space 117, shown in Figure 7.

Referring to Figures 2 and 3, it will be seen that the shaft 102 of the impression cylinder carries at its left end a gear wheel 138. This gear wheel meshes with an intermediate idler gear wheel 139 which also meshes with and is driven by the gear 77 on shaft 72 which rotates twice as fast as shaft 69 being connected by gears 68 on shaft 69 to a gear on shaft 72 of the same size as gear 77. The impression cylinder is, by this gear train, rotated continuously from the shaft 72 and the proportions of the gears are such that the impression cylinder makes two revolutions for each revolution of the shaft 69. The cam wheel 137 which actuates the toggles for raising and lowering the impression cylinder, being driven by the shaft 69, will therefore effect the opening and closing of the toggles once during every two revolutions of the impression cylinder and the cam groove 136 is so formed and ar-

ranged that the impression cylinder is lowered just after the printing stroke of the bed commences and is raised just before the end of this stroke.

In case a sheet of paper is not supplied to the cylinder, it is essential to prevent the cylinder from being lowered into printing position or if it has been lowered to have it raised out of printing position in order to prevent the impression from being received by the packing, with which the cylinder is covered. Referring to Figure 1, it will be observed that the toggles will not be actuated when the hook 130 is out of engagement with the pin 129 and therefore when it is desired to prevent the impression cylinder from being lowered to the printing position or to permit it to be lifted out of printing position, means for lifting the hook 130 out of engagement with the pin 129 are actuated. This means consists of a lever 142 pivoted to the frame 40 at 143 and carrying a pin 144 which engages the underside of the extension 145 on the link 131. By rocking the lever 142 so as to raise the pin 144 the hook 130 may be lifted out of engagement with the pin 129 and for the purpose of so rocking the lever 142, the latter has connected therewith a rod 146 having its lower end connected with a pedal 147 which is vertically slidable on the rod 148, the latter being secured to the frame 40. The pedal 147 is engaged by the operator's foot and depressed and thereby rocks the lever 142 to disengage the hook 130 from the pin 129. For the purpose of raising the pedal 147 and rocking the lever 142 in the opposite direction, a spring 149 has one end connected with the frame 40 and the other end with the rod 146. A spring-pressed detent 150 is also provided for the purpose of automatically engaging and holding the pedal 147 in the depressed position so as to permit the press to run without raising and lowering the impression cylinder. The extension 145 on the rod 131 is provided with a depending lug 151 which is adapted to engage the pin 129 after the rod 131 has been lifted. This will insure the opening of the toggles, even after the hook 130 has been lifted, and thereby eliminates the possibility of leaving the impression cylinder in the lowered position by disengaging the hook 130 from the pin 129. After the toggles have been opened, however, the hook 130 will move to and fro without engaging the pin 129 and therefore the cylinder will not be lowered into printing position until the hook 130 has been lowered to permit engagement with pin 129.

It is desirable to have means whereby the toggles may be opened at any time during the printing operation and in order to effect this result the lever 142 is provided with a lug 152 on its upper side, (see Fig. 9) which is adapted to engage the arm 128 and move

the latter to the left and thus open the toggles. The lug 152 engages the arm 128 after the hook 130 has been lifted out of engagement with the pin 129 and when the pedal 5 147 is depressed to its lowest position.

Secured to the frame 40, on opposite sides thereof, are the upwardly projecting brackets 153 and 154, these brackets supporting a feed board and a feed table and 10 automatic feeding mechanism which will be hereinafter described in detail. The feed board 155 is pivoted to the brackets 153 and 154 at 156 and 157, respectively. The forward end of the feed board is supported on 15 adjustable screws 158 and 159 which are carried by lugs on the brackets 98 and 99 respectively. Referring to Figures 3 and 4, it will be seen that the forward end of the feed board is provided with a projecting 20 plate 160 and beneath this plate and projecting forwardly therefrom are the fingers 161, which are adjustably carried on the underside of the feed board by means of a T-rail 162. The fingers 161 support the forward edge of the sheet of paper and gages 163 cooperate with the fingers 161 to properly position the forward edge of the sheet. These gages will be described in detail hereinafter.

25 The brackets 201 and 202 have journaled therein the shaft 195, this shaft being extended beyond the bracket 201 and loosely carrying an arm 247 which is pivotally connected with the upper end of the rod 234.

30 The arm 247 is provided with a laterally projecting lug in which is adjustably secured a screw 248, the lower end of which is adapted to engage the arm 249 which is secured to the shaft 195. The shaft 195 carries arms 250 which are adjustably secured on the shaft by means of clamping screws 251. The arms are bored out to receive a stem 252 which carries the front gage or sheet stop 163, the latter being secured 35 to the stem by means of a clamping screw 253 (see Figure 5). The end of the stem 252, in the arm 250, is internally threaded as shown at 254 to receive an adjusting bolt 255, this bolt being journaled at 256 in the arm 250 and being secured against longitudinal movement by means of the collar 257 and the head 258. The stem 252 is normally clamped in the arm 250 by means of the 40 clamping screw 259 and when this screw is released the gage 163 may be adjusted longitudinally of the feed board by turning the bolt 255.

45 The gages 163 are lowered against the fingers 161 by lifting the rod 234, the stripper fingers 231 being simultaneously moved to a position to receive the sheet from the cylinder. Just before the grippers engage the forward edge of the sheet on the feed board, the rod 234 is actuated to simultaneously lift the gages 163 and rollers 198

to permit the sheet to pass thereunder. The actuation of the rod 234 to raise and lower the gages and also the rollers and stripper fingers is accomplished by connecting the lower end of the rod with a lever 260 which is pivoted at 261. The lever 260 carries a cam roller 262 which engages the periphery of the cam wheel 263, the latter being suitably formed to actuate the gages and stripper fingers at the proper times in the cycle 75 of operations.

For the purpose of automatically conveying the sheets forward into position to be taken by the cylinder, I have arranged feeding tapes 264 on the surface of the feed board (see Figure 4). These feed tapes are carried at the forward end of the feed board by suitable pulleys or tape wheels 265 which are mounted on a shaft 266, this shaft being supported in bearings 267 which are adjustable longitudinally of the feed board and secured in position by suitable screws 268. At the rearward end of the feed board, the tapes are carried on pulleys or tape wheels 269 mounted on a shaft 270, this shaft being journaled in the feed board pivots and being driven by a gear train consisting of the gears 271, 272 and 273 (see Figure 3). The gear 271 is secured on the shaft 270, and the intermediate gear 272 is loosely arranged on the shaft 274. The gear 273 is secured to the feed roll shaft 275 journaled in the brackets 153 and 154, the shaft 275 carrying a bevel gear 276 which meshes with a gear 277 on the vertical shaft 278. The lower end of the shaft 278 is journaled in a housing 279 which is supported by means of a bracket 280 from the bracket 154. The shaft 278 is driven by means located in the housing 279 and the drive is controlled by a clutch operating handle 288 pivoted at 289 whereby the shaft 278 may be connected to the driving means of the press or disconnected therefrom.

Above the shaft 275, the brackets 153 and 154 have journaled therein a shaft 292, this shaft being driven from the shaft 275 by means of gear wheels 293, 294. (see Figure 2). Arms 295 and 296 are pivotally supported on the shaft 292 and are normally arranged immediately above the side portions of the feed board 155. The arms 295 and 296 are connected by cross-bars 297 and 298 and these bars support longitudinally extending bars 299 arranged above the feed tapes 264. The bars 299 are each provided with a series of openings 300 through which balls 301 project to press the paper against the feed tapes so that it will be carried forward thereby. Guards 302 are secured to the bars 299 and hold the balls 301 in position. The arms 295 and 296 carry at their forward ends a shaft 303 which supports fingers 304 a slight distance above the plate 160 and prevent the forward edge 110

110

115

120

125

130

of the paper from being lifted. The forward ends of the arms 295 and 296 are provided with feet 305 which rest on the feed board and support the arms in the position shown in Figure 4. The arms also carry a transverse shaft 306 on which are secured fingers 307, preferably provided with rubber tips 308 which are adapted to engage the sheet, just before it strikes the front stops, and retard its movement, the shaft 306 being oscillated for this purpose. The oscillating mechanism for the shaft 306 comprises an arm 309 secured to the shaft and having pivoted thereto one end of a rod 310, the opposite end of this rod being pivoted to the lower end of a lever 311. The lever 311 is supported on a pivot carried by the arm 296 and has at its upper end a roller 312 which engages the periphery of a cam wheel 313 secured on the shaft 292. The cam wheel 313 is so formed that the fingers 307 will be depressed once for each revolution of the shaft 292.

Arms 295 and 296 also carry a shaft 314 on which the arms 315 are secured, and adjacent the arms 315 the shaft 314 has loosely mounted thereon the feelers 316. The feelers 316 are provided with comparatively large openings 317 into which project small pins 318 carried by the arms 315. As shown in Figure 4, the forward end of the feeler is arranged just above the plate 160, and the plate below the end of the feeler is provided with an opening 319 through which the end of the feeler is adapted to project when depressed and there is no sheet of paper on the plate. The feeler is normally supported above the plate 160 by the engagement of the pin 318 with the rearward side of the opening 317 as shown in Figure 4, and when the shaft 314 is rocked to swing the arm 315 forwardly, the end of the feeler will be permitted to drop and in case there is a sheet of paper on the forward end of the feed board this will form a stop for the feeler, the arm 315 being permitted to move for a slight distance on account of the pin 318 being smaller than the opening 317.

Each of the feelers is provided with a rearwardly projecting toe 320 which is engaged by an arm 321 on the shaft 322. The shaft 322 is journaled in the arms 295 and 296 and has secured thereto an arm 323 which is connected with one end of a rod 324 (see Figures 1 and 3). The opposite end of the rod 324 is pivoted to a swinging arm 325 and the extreme end of the rod is adapted to engage a pawl 326 which is pivoted at 327 to a lever 328. The lever 328 is pivoted to the bracket 153 at 329 and carries a cam roller 330 which engages the periphery of a cam wheel 331 on the shaft 292. The pawl 326 has a portion 326' (Figure 3) extending horizontally from the pivot 327 (see Figure 3) and this portion normally tends to

swing the lower end of the pawl toward the left, in Figure 1, and thereby hold the pawl in contact with the end of the rod 324.

The cam 331 oscillates the lever 328 and thereby moves the pawl 326 up and down in a substantially vertical path. As will be seen from Figure 1, a push rod 332 has its upper end arranged adjacent the end of the pawl 326 and adapted to be engaged by the latter. The upper end of the push rod 332 slides in a suitable guide 333 and the lower end of the push rod is connected with one end of a lever 334 which is pivoted at 335 to the bracket 153. The opposite end of the lever 334 is connected with a link 336, the lower end of which is pivoted to the extension 145 of the hook rod 130. It will be seen that by this construction, when the push rod 332 is depressed by the lever 328 the hook 330 will be lifted out of engagement with the pin 129 and this will prevent the lowering of the cylinder into printing position. The lever 328 is moved upwardly and the roller 330 held in engagement with the cam 331 by means of a suitable spring 337, as shown in Figure 1. The purpose of the mechanism just described is to automatically throw out or prevent the lowering of the cylinder into printing position in case a sheet of paper is not fed to the forward end of the feed board so it may be taken by the cylinder. The operation of this mechanism is as follows. The lever 328 is continuously rocked by the cam 331 and the pawl 326 raised and lowered thereby. When there is no sheet of paper at the forward end of the feed board the rocking of the shaft 314, by a mechanism to be described hereinafter, will permit the forward end of the feeler 316 to descend through the opening 319, and the rearwardly projecting toe 320 on the feeler will lift the arm 321 and thereby rock the shaft 322 so as to move the rod 324 toward the right in Figure 1. The lower end of the pawl 326 will be moved to a position to engage the upper end of the push rod 332 on the next downward movement of the pawl and when the lever 328 is rocked, with the parts in this position, the hook 130 will be lifted out of engagement with the pin 129 and the lowering of the cylinder prevented. It will be understood that the same result will be accomplished in case anyone of the feelers passes through the opening 319 therefor in the plate 160, and therefore the automatic throw out mechanism will operate in cases where the sheet is not in proper register with the stops 163.

For the purpose of regularly rocking the shaft 314, in timed relation to the other operations of the press, the shaft is provided with an arm 338 which has pivoted thereto one end of a rod 339, the opposite end of this rod being connected with a lever similar to the lever 311 and mounted on

the same pivot and actuated by a cam 340. The arms 295 and 296 have journaled therein a shaft 341 having secured thereon the arms 342 and 343. The arms 342 and 343 each carry two stub shafts and each of these shafts has journaled thereon a wheel 344 so that each of the arms carries two wheels. One of each pair of these wheels carries a rubber roller 345, and when the shaft 341 is rocked to move the wheels toward the feed board, the rubber rollers contact with the sheet of paper and move the paper transversely of the feed board against the usual side gage (not shown). The wheels 344 are rotated by means of a belt 343 which runs over an idler pulley 347 on the arm 295 and over a driving pulley 348 on the arm 296. The driving pulley 348 is carried by a shaft which also has arranged thereon a bevel gear 349, this gear meshing with a gear 350 on a transversely extending shaft carried by the arm 296. The latter shaft also carries a pulley 351 which is driven from a pulley 352 on shaft 292 by means of a belt 353.

The shaft 341 is rocked in timed relation to the other operations of the press by mechanism comprising an arm 354 secured on the shaft 341 and having pivoted thereto one end of a rod 355, the opposite end of which is connected with a lever 356 pivoted to the arm 295 and oscillated by means of a cam 357 on shaft 292.

From the foregoing, it will be seen that I have provided means for automatically feeding the sheets of paper over the feed board and into register with the front and side gages. I have also provided automatic means for preventing the lowering of the impression cylinder in case the paper is not fed to the front gages or is not fed properly thereto. It will also be noted that all of this mechanism is driven from the vertical shaft 278 and it is possible to throw this mechanism into and out of operation by means of the lever 288. In case any of the feeding mechanism becomes disarranged all of the mechanism may be thrown out of operation by the lever 288, and the arms 295 and 296 with the mechanism carried thereby may be swung upwardly out of the way to permit hand feeding from the feed board. The position to which the arms 295 and 296 are swung is indicated in broken lines in Figure 4 at 358, and it will be noted that in this position the arms engage and are supported by pins 359, these pins being arranged in lugs 360 on the brackets 153 and 154. It will be noted that in swinging the arms 295 and 296 to the inoperative position, as just described, none of the mechanism carried thereby is disturbed, and when the arms are again swung down to the feed board the parts are in their operative position.

After the arms 295 and 296 have been swung to the inoperative position the feed board 155 may be swung to the position shown in dotted lines at 361 in Figure 4, and since the shaft 270 is on the axis of the pivots of the feed board, the feed tapes and their driving mechanism need not be disturbed. When the feed board has been raised as just described, access may be had to the inking mechanism to be described hereinafter.

Associated with the automatic paper conveying mechanism is a separating mechanism for feeding individual sheets forward from a pile on the feed table 362. The table 362 is provided with downwardly extending brackets 363 at opposite sides thereof which are pivoted on a shaft 364 suitably supported on the brackets 153 and 154. The brackets 363 have slotted sector shaped lower ends which are engaged by clamping bolts 365 for the purpose of clamping the feed table in any desired position. An extension plate 366 is hinged to the forward edge of the feed table 362 and is supported on arms 367 which are secured to brackets 368 by means of pivot pins 369, these arms carrying rubber pads in their upper sides. The brackets 368 are carried by the shaft 364, and are provided with adjusting screws 370 which engage the lower sides of the arms 367 and adjustably support the latter. The arms 367 are held against the adjusting screws 370 by means of springs 371. The forward ends of the arms 367 are adjacent the surface of the feed roll 372 on shaft 275 and above this feed roll and the arms 367 are feed wheels 373 provided with rubber inserts 374 which are adapted to engage the top sheet of the pile on the feed table 362 and draw this sheet forwardly to the feed roll 372. A shaft 375 carried by the arms 295 and 296 has adjustably secured thereon brackets 376 which support guards 377 which extend rearwardly above the feed roll 372, and substantially parallel with the face of the feed wheels 373 so as to prevent the pile of sheets from working down against the feed wheels.

The shaft 375 also carries brackets 378 on which are pivotally mounted arms 379 which carry rollers 380, these rollers pressing against the top of the feed roll 372 and cooperating with the latter to feed the sheets forward to the feed board. The brackets 378 carry adjustable screws 381 between the lower ends of which and the arms 379 are springs 382, these springs normally pressing the rollers 380 against the feed roll.

The feed board 155 has secured to the rear edge thereof an extension plate 383 and a plate 384 extends from the rearward edge of the plate 383 to a position over the feed roll 372 and this plate is supported by means of brackets 385 carried by the shaft 274.

With the foregoing construction, the sheets will be drawn forward by the feed wheels 373 which are constantly rotated and carried between the rollers 380 and the feed roll 372. The feed roll 372 being also constantly rotated will carry the sheet forward between the guards 377 and the plate 384 until the forward edge of the sheet is caught between the feed tapes 264 and the balls 301. The feed tapes will then carry the sheet forward to the front gauges hereinabove referred to. The feed wheels 373 have a circumference of a sufficient length to handle the longest sheets which the machine is capable of printing, and the speed of the feed wheels is so timed with relation to the other parts of the press that the sheets will be fed forward in time with the revolutions of the impression cylinder.

Although a specific embodiment of the invention has been illustrated and described it is obvious that the structure may be varied in its details without departing from the spirit of the invention.

Having thus described my invention, what I claim is:

1. In a printing press, the combination of a pivotally supported feed board, a pivotally mounted frame arranged above said board, said frame and board having cooperating sheet manipulating means, the portion of said means on the board being disposed under said frame, and mechanism to operate said means, the pivotal mountings of the feed board and frame being constructed and arranged so that the frame may be raised to permit sheets to be fed from the feed board and both the frame and feed board may be raised to give access to parts thereunder without disconnecting said mechanism.

2. In sheet feeding mechanism, the combination of a pivotally supported feed board, a pivotally mounted frame arranged above the board, and cooperating sheet manipulating means carried by said frame and board, the portion of said means on the board being under said frame.

3. In a printing press, the combination of a feed board pivotally mounted at one end, a frame arranged over the board and pivotally supported at one end, whereby it may be raised from the feed board, sheet advancing means carried by said board and sheet registering mechanism carried by said frame and movable away from the board with the frame when the frame is raised.

4. In a printing press, the combination of a pivotally supported feed board, a frame pivotally arranged over the board and having its pivots parallel to the feed board pivots whereby it may be raised from the feed board, sheet registering mechanism carried by one of said pivoted parts, a shaft

carried by the frame parallel with said pivots, means to actuate said mechanism from said shaft, and means to rotate said shaft including a wheel coaxial with the frame pivots, whereby the frame may be raised without disconnecting said shaft rotating means.

5. In a printing press, the combination of a feed board pivotally mounted to be swung upward, a frame arranged over the feed board and pivotally mounted to be swung upward from the feed board, sheet advancing tapes carried by said board, sheet registering mechanism carried by one of said pivoted parts, means for operating said tapes, and means for actuating said mechanism including a wheel disposed coaxially with the pivots of one of said parts.

6. In a printing press having a throw off device, the combination of a pivotally supported feed board, a pivotally mounted frame arranged over the board, sheet advancing means carried by said board, means for driving said advancing means, sheet registering mechanism carried by one of said pivoted parts, means for actuating said mechanism, sheet controlled means carried by said frame having a connection with said throw off device for governing the action of the same, said connection, driving means, and actuating means constructed and arranged to permit the frame and board to be raised and lowered without disconnecting the same.

7. In a printing press, in combination, a cylinder, means for advancing sheets to cylinder picking up position, said means comprising separately hinged upper and lower devices to permit the said devices to have raising movements from operative position, one of said devices including the feed board.

8. In a printing press, the combination of a feed board, a shaft, a frame pivotally mounted on said shaft, and normally supported above the feed board, sheet registering mechanism carried by said frame, and adapted to cooperate with a sheet on the feed board and means for driving said mechanism from said shaft and adapted to permit the frame to be swung upwardly from the feed board without disturbing the driving relation to said shaft.

9. In a printing press, the combination of a pivotally mounted feed board, endless tapes carried by the feed board, means for driving said tapes including a wheel mounted coaxially with the axis of the pivots of the feed board, a frame arranged over the feed board and adapted to be removed therefrom, and means carried by said frame and adapted to cooperate with said tapes to feed the sheet forward on the feed board.

10. In a printing press, the combination of a pivotally mounted feed board, endless

5 **tapes carried by the feed board, means for driving said tapes including a wheel mounted coaxially with the axis of the pivots of the feed board, a frame arranged over the feed board and having pivots with their axes parallel with the pivots of the feed board, whereby the frame is adapted to be swung upwardly from the feed board, and means carried by said frame and cooperating with said tapes to feed the sheet forward on the board.**

10 **11. In a printing press having a throw off device, the combination of a pivotally mounted feed board, a pivotally mounted frame arranged over the board, sheet advancing means carried by said board, and sheet controlled means carried by said frame having a connection with said throw off device for governing the action of said device, said connection constructed and arranged to permit the frame to be raised and lowered.**

15 **12. In a printing press having a throw off device, the combination of a feed board, a frame arranged above the board, means for supporting the frame for movement to and from the board whereby the frame may be moved away to expose the board, and sheet controlled means carried by said frame having a connection with said throw off device for governing the action of said device, said connection being constructed and arranged to permit the frame to be moved to and from the board.**

20 **13. In a printing press, the combination of a pivotally supported feed board, endless tapes associated with said board, means for driving said tapes, a pivotally mounted frame arranged over the feed board, means associated with said frame adapted to cooperate with said tapes to feed the sheet forward on said board, sheet registering mechanism carried by one of said pivoted parts, and means for actuating said tapes and mechanism constructed and arranged to permit the frame and board to have raising movements without disconnecting said means.**

25 **14. In a printing press, the combination of a feed board, a shaft arranged rearwardly thereof, a frame pivoted on said shaft and normally arranged over the feed board, mechanism carried by said frame for manipulating a sheet on the feed board, and operating means for said mechanism driven by said shaft and arranged to permit said frame to be swung upwardly from the feed board without disturbing the relation of said operating means to said shaft.**

30 **15. In a printing press, the combination of a feed board pivotally mounted at its rearward end, a shaft having its axis coincident with the axis of the feed board pivots, means for feeding the sheet forward on**

35 **the feed board and operated by said shaft, a shaft arranged parallel to the first-mentioned shaft, a frame pivoted on the second-mentioned shaft and normally arranged over the feed board, sheet registering mechanism carried by said frame, and means whereby said sheet registering mechanism is driven from said second-mentioned shaft.**

40 **16. In a printing press, the combination of a feed board pivotally mounted at one end, a shaft having its axis coincident with the axis of the feed board pivots, endless tapes carried by the feed board and driven from said shaft, a frame arranged over the feed board and adapted to be removed therefrom, and means carried by said frame and adapted to cooperate with said tapes to feed the sheet forward on the feed board.**

45 **17. In a printing press, the combination of a feed board pivotally mounted at its rearward end, a shaft having its axis coincident with the axis of the feed board pivots, endless tapes carried by the feed board and driven by said shaft, a frame arranged over the feed board and having pivots with their axes parallel with the feed board pivots, whereby the frame is adapted to be swung upwardly from the feed board, and means carried by said frame and cooperating with said tapes to feed the sheet forward on the feed board.**

50 **18. In a printing press, the combination of a feed board, a frame arranged over said feed board, a shaft carried by said frame and extending transversely of the feed board, a bracket carried by said shaft, a side registering wheel carried by said bracket, means for rotating said wheel, and means for oscillating said shaft to move the wheel into and out of engagement with the sheet.**

55 **19. In a printing press, the combination of a feed board, a frame arranged over the feed board, a shaft carried by said frame, a bracket carried by said shaft and adjustable longitudinally thereof, a side registering wheel carried by said bracket, means for rotating said wheel, and means for oscillating said shaft to move the wheel into and out of engagement with the sheet.**

60 **20. In a printing press, the combination of a feed board, means thereon for feeding the sheets forward, a frame arranged over the feed board, a shaft carried by said frame, a bracket on said shaft and adjustable longitudinally thereof, a side registering wheel carried by said bracket, an endless belt carried by said frame and adapted to rotate said wheel in any position of the bracket, and means for operating said belt.**

65 **21. In a printing press, the combination of a feed board, means thereon for feeding sheets forward, a shaft at the rear of the feed board, a frame arranged over the feed board, a shaft carried by said frame, a**

bracket on said second shaft, a side registering wheel carried by said bracket, and means whereby said wheel is rotated from the first-mentioned shaft and independently of the 5 feed board.

22. In a printing press, the combination of a feed board, means thereon for feeding the sheets forward, a shaft arranged rearwardly of the feed board, a frame arranged over the 10 feed board and pivoted to said shaft, a shaft carried by said frame, a bracket on said 15 second-mentioned shaft, a side registering wheel carried by said bracket, means for rotating said wheel from the first-mentioned shaft, and means for oscillating the second-mentioned shaft from the first-mentioned shaft, said wheel rotating and shaft oscillating means being adapted to permit said frame to be swung upward from the feed 20 board without disturbing the operative connections between the first-mentioned shaft and the second-mentioned shaft and wheel.

23. In a printing press, the combination of a feed board, a shaft arranged above and at 25 the rear of the feed board, a frame pivotally mounted on said shaft and normally arranged over the feed board, a shaft carried by said frame, sheet-retarding fingers carried by said second-mentioned shaft, and 30 means whereby the second-mentioned shaft is oscillated from the first-mentioned shaft.

24. In a printing press, the combination of a feed board, a shaft arranged above and at the rear of the feed board, a frame pivotally 35 mounted on said shaft, a shaft carried by said frame, sheet-retarding fingers carried by said second-mentioned shaft, a cam on the first-mentioned shaft, and means actuated by 40 said cam to oscillate the second-mentioned shaft.

25. In a printing press, the combination of a feed board, a frame supported above the feed board, a pair of alined pulleys carried by said frame on opposite sides thereof, an 45 endless belt operating on said pulleys, and a side registering wheel actuated by said belt.

26. In a printing press, the combination of a feed board, a frame supported above the 50 feed board, a pair of alined pulleys carried by said frame on opposite sides thereof, an endless belt operating on said pulleys, and a pair of side registering wheels actuated by 55 said belt.

27. In a printing press, the combination of a feed board, a frame supported above the feed board, a pair of alined pulleys carried by said frame at the opposite sides thereof, an 60 endless belt operating on said pulleys, a shaft carried by said frame, a plurality of brackets on said shaft, and side registering wheels carried by said brackets and adapted to be rotated in either direction by said belt.

28. In a printing press, the combination of

a feed board, a frame supported above the 65 feed board, a plurality of shafts carried by said frame, an impression cylinder, means for raising and lowering the impression cylinder, a detector finger carried by one of said shafts adapted to detect the absence 70 of a properly registered sheet on the feed board, means whereby the other of said shafts is rocked by said detector finger, and means actuated by the last-mentioned shaft 75 to throw the cylinder raising and lowering means out of operation.

29. In a printing press, the combination of a pivotally supported feed board, a frame supported on pivots parallel to the feed 80 board pivots and arranged over the feed board, mechanism carried by the said frame for manipulating the sheet on the feed board and operating means for said mechanism including a shaft carried by the frame parallel to its pivots, and means to actuate said shaft 85 arranged to permit said frame to be swung upwardly from the feed board without disconnecting said actuating means.

30. In a printing press, the combination of a feed board, a feed roll, a feed table inclined toward said feed roll and arranged directly in front thereof adapted to support a pile of sheets, means for adjusting the angle of inclination of the feed table, sheet separating means for advancing the sheets 90 from the pile to said feed roll, and means cooperating with the feed roll to advance the sheets to the feed board.

31. In a printing press, the combination of an impression cylinder, a feed board, front 95 gages for the sheet on the feed board, a shaft on which said gages are mounted, an arm on said shaft, a lever loosely mounted on said shaft, means for oscillating said lever once for two revolutions of the cylinder, an adjustable screw operatively connecting said arm and said lever, said screw carried by one 100 part and directly engaging the other, and means for oscillating said lever, said screw permitting said lever to move in one direction 105 independently of said shaft.

32. In a sheet feeding mechanism, the combination of a feed board, a frame arranged over said board, cooperating sheet manipulating means carried by said frame and board, and means for actuating said sheet manipulating means, said frame and board being separately pivoted for raising movements from operative position without disconnecting said actuating means.

33. In a printing press, the combination of a pivotally supported feed board, a shaft having its axis parallel with the axis of the feed board pivots, endless tapes associated with the feed board and driven from said shaft, a frame arranged over the feed board and adapted to be removed therefrom, and means carried by said frame adapted to co-

operate with said tapes to feed the sheet forward on the feed board.

34. In a printing press, a cylinder, a feed table, mechanical means for advancing 5 sheets to cylinder picking-up position on said table, said means comprising separately hinged upper and lower sections to permit the sections to have raising movements from

operative position and one of said sections carrying the feed board.

In testimony whereof I affix my signature in presence of two witnesses.

WILLIAM M. KELLY.
